MECHANISM FOR OPERATING ORE BIN GATES

Filed Sept. 21, 1925

2 Sheets-Sheet 2

UNITED STATES PATENT OFFICE.

WILLIAM S. ORR, OF MASSILLON, OHIO, ASSIGNOR, BY MESNE ASSIGNMENTS, TO CENTRAL ALLOY STEEL CORPORATION, OF MASSILLON, OHIO, A CORPORATION OF NEW YORK.

MECHANISM FOR OPERATING ORE-BIN GATES.

Application filed September 21, 1925. Serial No. 57,552.

The present improvements relate more particularly to means for controlling the discharge of material from bins or hoppers of the type shown for example in U. S. Patent No. 702,731 to F. K. Hoover et al., dated June 17, 1902, but it will be understood that the invention is not necessarily limited to this particular type of bin or gate any more than it is limited to the handling of any particular kind of material. One object of the invention is to provide means whereby the discharge of material from the bin or pocket, in which it is contained, may be controlled and effected by a car designed to receive such material for the purpose of transporting same. In this way the proper location or spotting of the car is assured and the loading operation may be made more or less automatic. A further object of the invention is to provide a mechanism for the purpose in hand which will be relatively simple and so free from mechanical troubles, requiring a minimum amount of attention in its upkeep.

To the accomplishment of the foregoing and related ends, the invention, then, consists of the means hereinafter fully described and particularly pointed out in the claims, the annexed drawings and the following description setting forth in detail certain mechanism embodying the invention, such disclosed means constituting, however, but one of various mechanical forms in which the principle of the invention may be used.

In said annexed drawings:—

Fig. 1 is a side elevation with parts shown in section of my improved ore bin gate operating mechanism, the car whereon such mechanism is in part mounted appearing in end elevation;

Fig. 2 is a side elevation of such car, the portions of the bin mechanism proper, wherewith the mechanism on the car cooperates, being shown in dotted outline; and Figs. 3 and 4 are broken front elevations of the bin gate and associated parts.

Only the lower portion of the bin or hopper 1, wherein the body of material which is to be transferred to the car 2 is contained, appears in Fig. 1. Such bin has converging front and rear walls in combination with a roller 3 journaled below the same and forming a movable bottom wall for the discharge outlet of the hopper. It will be noted that

the rear wall 4 of the latter extends substantially into contact with the periphery of roller 3, while the front wall 5 of said hopper terminates some distance above the roller, and that in the outlet opening, thus formed, a series of transverse bars or louvers 6 is mounted. The location of the cylinder or roller 3 relatively to the discharge opening of the hopper is such that when said cylinder is at rest, the line marking the underlying angle of repose of the material in the hopper falls just within the cylinder and the escape of material by gravity is thus checked. The louver bars 6 present a broken surface for the passage of material being discharged and more or less agitate and break up the latter as well as prevent the arching of the material in the bottom of the bin which might prevent its free flow downwardly onto the cylinder.

The mechanism of present interest has to do with the rotation of the roller or cylinder 3 whereby it will thus be seen the discharge of material from the hopper is effected and controlled. The direction of rotation of the cylinder is indicated by the arrow in Fig. 1 and for the purpose of imparting rotative movement thereto when desired, the cylinder is provided at one end with a large gear 7.

Moreover, in order definitely to stop the discharge of material when a given amount has been received in car 2, which as shown is a scale car designed to weigh and thus measure the quantity of such material, as is necessary for instance in blast furnace operation, a retarding or guard gate 8 is provided. This gate is intended to extend the entire length of the drum, being attached to the forward ends of levers 9 that lie beyond the end walls 10 of the corresponding bin and are fulcrumed at points 11 adjacent the rear wall 4. When material is being discharged, the gate will occupy the raised position shown in full lines in Fig. 1, but upon disconnecting (as hereinafter described) the gearing provided for rotating the cylinder or roller 3, such gate is dropped into contact with the drum, as shown in dotted outline in said figure.

A scraper 12 is also associated with the roller, being pivotally supported at its respective ends and held in contact with the surface of the roller by means of a tension spring 13.

The mechanism whereby the roller is rotated and the guard gate 8 raised and lowered is located on the scale car. This driving mechanism consists of a pinion 15 which is adapted to mesh with gear 7, said pinion in turn being driven through an idler pinion 16, this idler being driven through a train of gears 17 by a motor 18. Pinion 15 is mounted in a supplemental frame or housing 19 that is oscillatory about the same shaft 20 whereon idler pinion 16 is mounted, oscillation of frame 19 being secured by means of a fluid pressure cylinder 21 provided with a piston 22 that is suitably connected with said frame. The oscillatory frame 19 also serves to operate the guard gate, being provided to this end with an arm 23 that projects beyond pinion 15 so as to engage with a roller 24 on the lower end of a link 25, the upper end of which is attached to lever 9 forwardly of the latter's fulcrum point 11. Upward movement of the frame may be limited in any suitable way so as to prevent the teeth of pinion 15 from meshing too deeply with those of gear 7, e. g. by means of a stop 26 on said frame and a co-operative stop 27 attached to the bin structure or the framework whereby the latter is supported, as will be readily understood.

As a safety precaution, pinion 16 is loose on shaft 20 and is located adjacent to a magnetic clutch 30 which when energized grips the pinion and thus transmits power from the motor drive to pinion 15. Said clutch will be operated by a push button 31 from a pulpit 32 or by the first point on the controller 33. In place of such magnetic clutch, any other suitable type of clutch may be employed, the object being to allow the teeth of pinion 15 and gear 7 easily to slide in mesh. It should be noted in this connection that such teeth will be designed with sharp points so that their ends will not hit in engaging and due to the fact that pinion 16 is loose on its shaft, said pinion 15 will be free to revolve enough to adjust itself to the teeth of the gear 7. The magnetic clutch serves the further purpose of permitting slippage in the drive in case the material should in any way lodge against the discharge roller or gate so as to prevent the latter from turning.

The operation of the mechanism as a whole may now be briefly set forth. When the scale car is brought into position beneath the discharge gate of the bin or hopper, the frame 19 will of course be lowered so that the pinion 15 will not strike the gear 7. It will be noted that as shown in Fig. 2, two bins with a corresponding number of operating mechanisms therefor are shown as adapted simultaneously to discharge into the car, but it of course is a matter of indifference, so far as the principle of the in-

vention is concerned, whether the car be arranged to thus receive material from one or a plurality of bins. The car having been stopped at the proper location to allow pinion 15 to mesh with gear 7, air or equivalent pressure fluid is admitted to cylinder 21 with the result, first, that the guard gate 8 is raised in the manner hereinbefore indicated and such pinion thereupon brought into mesh with the gear which it is to drive. Motor 18 is then started up and the gate revolved through the magnetic clutch or its equivalent until the proper amount of material has been discharged into the car. When this point is reached, the inverse operation is performed, i. e. the air is exhausted from cylinder 21 so as to unmesh the pinion 15 from the gear 7 and the guard gate 8 is allowed to drop. Thereupon the car may be moved away.

Compressed air is most conveniently employed for operating the frame 19 on account of the fact that air will be required for the purpose of braking the car and the air cylinder 21 when containing air under pressure will take care of any misalignment of track or drooping of the car due to compression of the springs thereof by the material being loaded. The means in question, in other words, provide a very flexible arrangement and one that makes unnecessary the precise alignment of bin and car. The pinion 15, moreover, will desirably have a face longer than the face on the gear 7 so as to allow for a certain amount of variation in the location of the car.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In mechanism of the character described, the combination of a bin having a movable guard and a means whereby material may be discharged from said bin; a car adapted to receive such material when properly positioned beneath said bin; and means for displacing said guard and means for actuating said discharge means carried by and operable from said car.

2. In mechanism of the character described, the combination of a bin having a movable guard and a means whereby material may be discharged from said bin; a car adapted to receive such material when properly positioned beneath said bin; and means for raising said guard and means for actuating said discharge means carried by and operable from said car.

3. In mechanism of the character described, the combination of a bin having a

- movable guard and a means whereby material may be discharged from said bin; a car adapted to receive such material when properly positioned beneath said bin; means for actuating said discharge means, and means for raising said guard carried by and operable from said car, said means including a link connected with said guard, and an oscillatory frame mounted on said car and adapted when raised to engage said link and raise said guard.
4. In mechanism of the character described, the combination of a bin having a rotary discharge control whereby material may be discharged from said bin; a movable guard and means carried by and operable from said car adapted successively to raise said guard and thereupon rotate said discharge control.
5. In mechanism of the character described, the combination of a bin having a rotary discharge control whereby material may be discharged from said bin and a movable guard; a car adapted to receive such material when properly positioned beneath said bin; and means for actuating said discharge control carried by and operable from said car, said means including a gear attached to said discharge control, a pinion bodily movably supported in said car and adapted in one position to mesh with said gear, and a motor connected to drive said pinion.
6. In mechanism of the character described, the combination of a bin having a rotary discharge control whereby material may be discharged from said bin; a movable guard adjacent the rotary discharge control; a car adapted to receive such material when properly positioned beneath said bin; and means for actuating said discharge control carried by and operable from said car, said means including a gear attached to said discharge control, a pinion bodily movably supported in said car and adapted in one position to mesh with said gear, a motor, and gearing including a clutch capable of slippage connecting said motor with said pinion.
7. In mechanism of the character described, the combination of a bin having a rotary discharge control whereby material may be discharged from said bin; a movable guard adjacent the rotary discharge control; a car adapted to receive such material when properly positioned beneath said bin; and means for actuating said discharge control carried by and operable from said car, said means including a gear attached to said discharge control, a pinion bodily movably supported in said car and adapted in one position to mesh with said gear, a motor, and gearing including a magnetic clutch capable of slippage connecting said motor with said pinion.
8. In mechanism of the character described, the combination of a bin having a rotary discharge control whereby material may be discharged from said bin; a movable guard adjacent the rotary discharge control; a car adapted to receive such material when properly positioned beneath said bin; and means for actuating said discharge control carried by and operable from said car, said means including a gear attached to said discharge control, a pinion bodily movably supported in said car and adapted in one position to mesh with said gear, a motor, and gearing including a magnetic clutch connecting said motor with said pinion, said clutch being capable of slippage and being operable from a distant point on said car.
9. In mechanism of the character described, the combination of a bin having a discharge control in the form of a rotary cylinder whereby material may be discharged from said bin; a movable guard adjacent the rotary discharge control; a car adapted to receive such material when properly positioned beneath said bin; and means for actuating said discharge control carried by and operable from said car, said means including a gear attached to said cylinder, an oscillatory frame mounted on one side of said car, a pinion carried by said frame and adapted in one position thereof to mesh with said gear, means for oscillating said frame, and a motor connected to drive said pinion.
10. In mechanism of the character described, the combination of a bin having a discharge control in the form of a rotary cylinder whereby material may be discharged from said bin; a movable guard adjacent the rotary discharge control; a car adapted to receive such material when properly positioned beneath said bin; and means for actuating said discharge control carried by and operable from said car, said means including a gear attached to said cylinder, an oscillatory frame mounted on one side of said car, a pinion carried by said frame and adapted in one position thereof to mesh with said gear, means for oscillating said frame, an idler pinion co-axial with the axis of oscillation of the latter, and a motor connected to drive said idler pinion.
11. In mechanism of the character described, the combination of a bin having a discharge control in the form of a rotary cylinder whereby material may be discharged from said bin; a car adapted to receive such material when properly positioned beneath said bin; and means for actuating said discharge control carried by and operable from said car, said means including a gear attached to said cylinder, an oscillatory frame mounted on one side of said car, a pinion carried by said frame and adapted in one position thereof to mesh with said

gear, a fluid-pressure actuated piston for oscillating said frame, and a motor connected to drive said pinion.

12. In mechanism of the character described, the combination of a bin having a gate in the form of a rotary cylinder whereby material may be discharged from said bin; a movable guard for said gate; a car adapted to receive such material when properly positioned beneath said bin; and means carried by and operable from said car adapted successively to raise said guard and thereupon rotate said gate, said means including

a gear attached to said cylinder, a link depending from said guard, a vertically oscillatory frame mounted on one side of said car and adapted when raised to strike said link and raise said guard, a pinion carried by said frame and adapted in such raised position thereof to mesh with said gear, means for oscillating said frame, and a motor connected to drive said pinion. 15 20
